UNITED STATES PATENT OFFICE.

WILLIAM J. WEISBROOK, OF MADISON, WISCONSIN.

HOG SCALDER.

Application filed September 10, 1924. Serial No. 736,921.

To all whom it may concern:

Be it known that I, WILLIAM J. WEISBROOK, a citizen of the United States, residing at Madison, in the county of Dane and State of Wisconsin, have invented certain new and useful Improvements in Hog Scalders, of which the following is a specification.

This invention relates to packing house equipment and particularly to a hog scalding.

An object of this invention is to provide a scalding for hogs which will keep the hogs under water all the time and will at the same time progress or move the hogs forward and at the same time to provide an improved conveyor and improved scalding and dipper and to generally simplify such machinery both in relation to the cost of manufacture and installation and also in its cost and convenience in operation.

With the foregoing and other objects in view, I have invented the device illustrated in the accompanying drawings, in which,

Figure 1 is a top plan view of my device; Figure 2 is a side elevation, partly broken away;

Figure 3 is a section at 3—3 Figure 1;

Figure 4 is a section at 4—4 Figure 1;

Figure 5 is a like section to Figure 4 but with the cranks in a different position.

Like reference characters represent like parts throughout the following specification and in the several views, in which, 2 is a tank or vat and 3 are longitudinal conveyor slats having an orbital movement by the turning of the cranks 3 and 4, which cranks are interconnected by chains 5 and 6 working on suitable sprockets such as 7 and suitably connected to some source of power not shown.

Carried by the slats 3 are cleats 8 passing beyond the edges of the slats and far enough to interlap and just clearing the next slat so that a complete roof is formed. The specific gravity of the hog being less than 1, its tendency is to float and it is intended that when

a hog is dropped into one end of the vat and pushed beneath the slats, that the cleats will push the hog onward underneath the conveyor slats and that these slats will at the same time progress or push the hog to the other end and that owing to the interlapping of the cleats that the hogs cannot bob up between the slats.

The relative sizes preferred would be, for a trough or vat twelve feet long by six feet wide, two crank shafts carrying eight slats with a four inch radius or eight inch stroke to the crank.

Claims:

1. In combination, a vat, and longitudinal conveyor slats within the vat, and means for reciprocating the slats vertically.

2. In combination in a hog vat, a plurality of longitudinal slats and means for moving the slats in an orbit.

3. In combination in a hog vat, a plurality of shafts provided with cranks, a plurality of slats carried by the cranks and cleats carried by the slats.

4. In combination in a hog vat, a plurality of cleats having an orbital movement, the cleats interlapping.

5. In combination in a hog vat, a sectional roof for the vat, and means for moving the longitudinal sections of the roof both longitudinally and vertically.

6. In combination with a hog vat, a movable roof for the vat, the roof provided with members having alternate vertical reciprocations.

7. In combination with a hog vat, a roof for the vat, the roof in sections, the sections alternately vertically reciprocating.

In testimony whereof I affix my signature in the presence of two witnesses.

WILLIAM J. WEISBROOK.

Witnesses:

OTTO NAFFZ,

A. J. KURTH.
